UNITED STATES PATENT OFFICE.

BENJAMIN SCARLES, OF CLINTON, MASSACHUSETTS, ASSIGNOR TO THE CLINTON WIRE CLOTH COMPANY, OF SAME PLACE.

METALLIC LATHING.

SPECIFICATION forming part of Letters Patent No. 394,403, dated December 11, 1888.

Application filed May 25, 1887. Serial No. 239,311. (No model.)

To all whom it may concern:

Be it known that I, BENJAMIN SCARLES, of Clinton, in the county of Worcester, State of Massachusetts, have invented a certain new and useful Improvement in Metallic Lathing, of which the following is a description sufficiently full, clear, and exact to enable any person skilled in the art or science to which said invention appertains to make and use the same, reference being had to the accompanying drawings, forming part of this specification, in which—

Figure 1 is a side elevation of my improved lathing in position for use on the wall of a room; Fig. 2, an isometrical projection of a portion of the same; Fig. 3, in cross-section, several forms of furring adapted for use in connection with this invention.

Like letters of reference indicate corresponding parts in the different figures of the drawings.

My invention relates to that class of metallic lathing in which the body, or lathing proper, is composed of wire-cloth and provided with furring-strips; and it consists in a novel construction and arrangement of parts, as hereinafter more fully set forth and claimed, the object being to produce a more desirable article of this character than is now in ordinary use.

The nature of the improvement will be readily understood by all conversant with such matters from the following explanation.

In the drawings, A represents the body of the lathing; B, the furring-strips; C, the binder, and D the stud or beam to which the lathing is attached. The body A is composed of wire-cloth, the warp, filling, and meshes of which may be of any suitable size.

40 The filling-strips B may be round, oval, angular, Ω -shaped, Λ -shaped, $\square$ -shaped, +shaped, or T-shaped in cross-section, as shown in Fig. 2, or of any other suitable construction.

45 The Ω -shaped are somewhat more expensive to manufacture than the solid strips, but are better adapted for heavy work.

The binder C is helical in form, consisting of a spirally-coiled wire of suitable length to span the web of cloth, its coils corresponding 50 approximately in length with the diameter of

the meshes, and being of such size as to project through them a sufficient distance to embrace the furring-strip.

The construction of the binder will be better understood by reference to Fig. 1 of the drawings, in which x x represent two of the warp-wires, and m m two of the filling-wires of the cloth composing the body A.

The binder is laid transversely on the face of the web of cloth between two of the filling-wires m m , and it will be observed that its coils coincide in length with the diameter of the meshes, or with the distance between the warp-wires x x . For instance, one of the coils commences at v , where it passes over one 65 of the warp-wires, and terminates at z , where it passes over the adjoining warp-wire, and so on throughout the length of the binder.

In assembling the parts of which the lathing is composed, the binder C is first placed 70 on the face of the cloth between the filling-wires m m , after which the furring-strip B is secured in position by inserting it in the projecting coils t of the binder at the back of the cloth, it being understood that the web is 75 provided with furring-strips and binders at intervals throughout its length.

The lathing is secured to the studding or beams of the room by staples b , but may be attached in any other suitable manner, if desired. It may also be applied to brick walls.

The cloth is designed to be made in long pieces or webs in the usual manner, and when provided with the furring-strips and binders it may be wound into cuts or rolls and kept 85 in stock for ready use; or the strips and binders may be applied to the cloth as it is used, if preferred, thus enabling the web to be wound into a more compact roll for storage or shipment.

I do not confine myself to disposing the furring-strips and their binders between the filling-wires, as they may be placed between the warp-wires, if desired, although I deem it preferable to arrange them transversely of the 95 web. Neither do I confine myself to constructing the binder with coils corresponding in length with the diameter of the meshes of the cloth, as they may be made of such length as to span two or more meshes.

The **N**-shaped furring-strips are somewhat more expensive to manufacture than the rods, but are better adapted for very heavy work.

It will be observed that the coils of the binder C do not pass around either the warp or filling wires, and as the binders are merely laid upon the face of the cloth with their coils projecting through its meshes the furring-strips may be very rapidly and firmly attached to the web at comparatively small expense, or detached, if occasion requires, without injuring the cloth.

Having thus explained my invention, what I claim is—

15 1. The combination of wire-cloth, a spirally-coiled binder, and a furring-strip, the binder being on one side of the cloth, the furring-

strip on the opposite side thereof, and the coils of the binder extending through the meshes of the cloth and around the furring-strip.

2. The combination of wire-cloth, a spirally-coiled binder, a furring-strip, the binder being on one side of the cloth, the furring-strip on the opposite side thereof, and the coils of the binder extending through the meshes of the cloth around the furring-strip, a beam or stud, and a staple embracing the furring-strip and one coil of the binder and passing through a mesh of the cloth into said beam or stud.

BENJAMIN SCARLES.
